UNITED STATES PATENT OFFICE.

EMIL SCHROEDER, OF NEW YORK, N. Y.

FLESHING AND SHAVING MACHINE.

SPECIFICATION forming part of Letters Patent No. 741,553, dated October 13, 1903.

Application filed April 20, 1903. Serial No. 153,443. (No model.)

To all whom it may concern:

Be it known that I, EMIL SCHROEDER, a citizen of the United States, and a resident of the city of New York, borough of Brooklyn, in the county of Kings and State of New York, have invented a new and Improved Fleshing and Shaving Machine for Raw and Dressed Furs or Skins, of which the following is a full, clear, and exact description.

The object of the invention is to provide a new and improved fleshing and shaving machine for quickly and accurately removing the surplus flesh from the under or flesh side of raw furs or skins and for paring or shaving the under or flesh side of dressed furs or skins to reduce the same to a desired uniform thickness.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement as arranged with a rotary disk cutter. Fig. 2 is an enlarged sectional plan view of the same on the line 2 2 in Fig. 1. Fig. 3 is an enlarged cross-section of a modified form of the disk cutter, having an overlaid knife-edge similar to a currier-knife edge. Fig. 4 is a front elevation of the improvement as arranged with a traveling endless-band cutter. Fig. 5 is a side elevation of the same. Fig. 6 is an enlarged sectional side elevation of part of the driven wheel and the endless-band cutter. Fig. 7 is a diagrammatic plan view of the cutter and the gage, having its gage edge set for drawing the fur or skin at angles over the cutter and gage edges. Fig. 8 is a like view showing the gage edges set equal on opposite sides of a cutter having currier-knife edges, and Fig. 9 is a perspective view of the stretcher-gage for the endless-band cutter.

In removing the flesh and other superfluous matter from the under or flesh side of raw fur or skin it has been the practice to first soak the skin, then to straighten it over the dull edge of the fleshing-knife, and to

finally pull the flesh side of the fur sidewise over the sharp edge of the fleshing-knife in order to remove the surplus material from the raw fur or skin. After the fur or skin is dressed in the usual manner it is then subjected to a second similar operation on a block or currier-beam and the use of a manually-operated currier-knife to pare or shave the skin to the desired thinness. Now both operations are not only very tedious and slow, but require considerable skilled labor.

With my improvement, presently to be described in detail, it is possible for an unskilled workman to properly remove the surplus flesh from the raw furs and skins for accurately paring or shaving the dressed furs or skins to a desired uniform thinness in a comparatively short time and without danger of injuring the fur or skin.

On a suitably-constructed standard or other support A is journaled a shaft B, carrying a pulley C, connected by belt with other machinery for imparting a high-speed rotary motion to the said shaft B. On the latter is secured the hub D' of a disk cutter D, arranged between the spaced members E' E² of a stretcher gage or guard E, carried by the support A, the said members E' E² consisting of each of a fixed section E³ and a hinged section E⁴, connected by a vertically-disposed hinge E⁵ to the fixed section E³.

The hinged sections E⁴ of the two members E' and E² can be swung toward and from each other at the front end of the machine, and for this purpose the said sections E⁴ are connected with each other at the top and bottom and outside of the peripheral cutting edge of the cutter D by left and right hand screw-rods F, so that on turning the latter in one direction the hinged members E' and E² swing toward each other, nearer to the faces of the cutter D, or the said members swing apart away from the disk faces when the screw-rods are turned in the opposite direction. This sidewise adjustment of the members E' E² relative to the cutter is necessary according to the nature of the fur or skin under treatment.

The operating edges E⁶ of the gage E are in the form of plates transversely adjustable on the hinged sections E⁴, and the terminals of the said edges are concentric with the periph-

ery of the cutter D, the annular cutting edge of which extends or projects beyond the said terminals, as plainly indicated in Figs. 1 and 2. Now the distance the cutter cutting edge 5 projects beyond the terminals of the edges E⁶ can be regulated by adjusting the edges transversely on the hinged sections E⁴ for regulating the depth of the cut of cutter on the furs or skins.

10 For the purpose mentioned each hinged section E⁴ is provided with transverse slots E⁷, through which extend the buttons E⁸, secured on the corresponding edge E⁶. One of the buttons E⁸ (preferably the middle one) is in 15 the form of a nut, in which screws a screw-rod G, mounted to turn in a bearing E⁹, held on the hinged section E⁴. Now by turning the screw-rod G the edge E⁶ is moved outward or inward, according to the direction in which 20 the screw-rod G is turned, to allow of adjusting the edges E⁶ to bring their terminals in proper relations to the peripheral cutting edge of the cutter D for a shallower or deeper cut of the cutter on the fur or skin.

25 On the support A, below the cutter D and its stretcher-gage E, is arranged a stretcher-knife H, over which the fur or skin is pulled to straighten the same previous to moving the fur or skin sidewise over the terminals 30 of the edges E⁶ and the interposed cutting edge of the cutter D, it being understood that for both operations the operator is preferably seated in rear of the machine to be in position for conveniently pulling the flesh side of 35 the furs tightly over the stretcher-knife H to straighten the skin and for conveniently drawing the flesh side of the fur or skin firmly and straight over the gage E and the cutting edge of the cutter.

40 The operation is as follows: In preparing the raw furs or skins for the machine the under or flesh side is soaked and laid in wet sawdust for a certain length of time—that is, until the skin is soft and pliable—and then 45 the flesh side of the fur is pulled tightly over the stretcher-knife H until the skin is straight and even, and then the operator slowly draws the skin sidewise, preferably from the left to the right, over the gage edges E⁶ against the 50 cutting edge of the rotary disk or band cutter, so that the cutting edge cuts the surplus flesh from the under side of the fur or skin to a depth corresponding to the distance the said cutting edge of the cutter projects beyond 55 the terminals of the gage edges E⁶. For fleshing large skins the edges E⁶ are preferably set relative to the cutter, as shown in Fig. 8, to move the skin in an oblique or angular direction over the cutter, and for small 60 skins I prefer the use of the curry-knife cutter shown in Figs. 3 and 4 and arrange the edges E⁶ alike on the sides of the cutter, as indicated in Fig. 7, to allow of drawing the fur approximately at right angles over the 65 cutter for the purpose mentioned. Now it is evident that by drawing the straightened flesh side of the fur or skin across the ma-

chine in the direction described the flesh surface of the fur or skin is in contact simultaneously with the gage-terminals—that is, at 70 two places located on opposite sides of the cut made by the cutting edge of the cutter—and hence the latter cannot cut deeper into the skin than the distance to which the cutting edge of the cutter projects beyond the 75 terminals of the gage edges E⁶, and an unskilled workman is therefore not liable to injure the fur or skin by causing too deep or irregular cuts. After the raw skin or fur is freed of the flesh it is dressed in the usual 80 manner, and then the above-described operation is repeated for paring or shaving the under side of the fur or skin to a uniform thinness, and this operation is preferably carried on over the cutter and gage set as shown in 85 Fig. 7.

I do not limit myself to the particular form of cutter above shown and described, as the same may be varied. For instance, as shown in Figs. 4 and 5, the cutter is in the form of 90 an endless band D², traveling under an idler-wheel I and over a driven wheel J, connected with suitable machinery for rotating the driven wheel, and the said endless band passed between the edges K' K² of a stretcher-gage 95 or guard K, attached to the support A and approximately similar to the stretcher-gage above described, with the exception that the terminals of the edges K' K² are straight and vertically disposed, while the terminals of 100 the edges E⁶ are segmental, as previously explained. The cutting edge of the traveling endless band D² projects, however, a distance beyond the terminals of the said edges K' K², the same as above described in reference to 105 the cutter D and the terminals of the edges E⁶.

In order to hold the cutter D² against lateral displacement, it is provided at its inner face a distance from the cutting edge with an annular shoulder D³, engaging corresponding annular grooves in the wheels I and J.

In using the modified form of machine the operator proceeds in the same manner as above described relative to the machine shown in Figs. 1 and 2, so that further description 115 thereof is not deemed necessary.

Having thus described my invention, I claim as new and desire to secure by Letters Patent—

1. A machine for fleshing and shaving raw and dressed furs or skins, provided with a mechanically-actuated cutter, having an annular curry-knife edge over which is drawn in a stretched condition the fur or skin, in a direction at an angle to the movement of the 120 cutter, as set forth.

2. A machine for fleshing and shaving raw and dressed furs or skins, comprising a stretcher-gage having spaced edges, over which the flesh side of the fur or skin is moved in a 125 stretched condition, and a mechanically-actuated cutter traveling between the said edges, in a direction at an angle to the movement of the fur or skin, the cutter having an

annular curry-knife edge projecting beyond the gage edges engaged by the fur or skin, as set forth.

3. In a machine for fleshing and shaving raw and dressed furs or skins, the combination of a stretcher-gage, with a mechanically-driven cutter having its blade passing between the gage edges and its cutting edge curved to form an annular curry-knife edge projecting beyond the edges of the gage, as set forth.

4. In a machine for fleshing and shaving raw and dressed furs or skins, the combination with a stretcher-gage having spaced adjustable edges, of a mechanically-driven cutter having its cutting-blade passing between the said edges and its cutting edge curved to form an annular curry-knife edge projecting beyond the said gage edges, as set forth.

5. In a machine for fleshing and shaving raw and dressed furs or skins, the combination with a stretcher-gage having spaced edges, adjustable toward and from each other, of a mechanically-driven cutter having its cutting-blade passing between the said gage edges and the cutting edge of the blade projecting beyond the terminals of the gage edges, as set forth.

6. In a machine for fleshing and shaving raw and dressed furs or skins, the combination with a stretcher-gage having spaced gage edges, adjustable transversely, and a mechanically-driven cutter having its blade traveling between the gage edges, the cutting edge of the blade projecting beyond the terminals of the said gage edges, as set forth.

7. In a machine for fleshing and shaving raw and dressed furs or skins, the combination with a stretcher-gage having spaced edges adjustable laterally and toward and from each other, of a mechanically-driven cutter having its blade traveling between the gage edges, the cutting edge of the blade projecting beyond the terminals of the said gage edges, as set forth.

8. In a machine for fleshing and shaving raw and dressed furs or skins, the combination with a stretcher-gage, of a rotary disk cutter, arranged relative to and operating in conjunction with the said gage, to remove sur-

plus material from the under side of the fur or skin on moving the latter across the gage and the traveling cutting edge of the cutter, as set forth.

9. A machine for fleshing and shaving raw and dressed furs and skins provided with a stretcher-gage having spaced members adjustable toward and from each other, as set forth.

10. A machine for fleshing and shaving raw and dressed furs or skins provided with a stretcher-gage having spaced members made in sections adjustable one on the other, and means for adjusting the members toward and from each other, as set forth.

11. A machine for fleshing and shaving raw and dressed furs or skins, provided with a stretcher-gage having spaced hinged members, each made in sections adjustable one on the other, and means for connecting the hinged members with each other, as set forth.

12. A machine for fleshing and shaving raw and dressed furs or skins, provided with a stretcher-gage having spaced hinged members each made in sections, means on each member for adjusting one section on the other section of the member, and a right and left hand screw-rod connecting the members with each other and arranged to move the members simultaneously toward or from each other, as set forth.

13. A machine for fleshing and shaving raw and dressed furs and skins, comprising a support, a mechanically-actuated cutter having an annular curry-knife edge and carried by the support, a stretcher-gage held on the support and having edges extending on opposite sides of the cutter, and a stretcher-knife fixed on the said support, as set forth.

14. A machine for fleshing and shaving raw and dressed furs provided with a cutter having an annular curry-knife edge, as set forth.

In testimony whereof I have signed my name to this specification in the presence of two subscribing witnesses.
